CURTAIN ROD CORNICE

Original Filed June 15, 1929

INVENTOR.
John Ajemian
BY *Thomas D. Donnelly*
ATTORNEY.

UNITED STATES PATENT OFFICE

JOHN AJEMIAN, OF DETROIT, MICHIGAN

CURTAIN ROD CORNICE

Application filed June 15, 1929, Serial No. 371,084. Renewed November 26, 1931.

My invention relates to a new and useful improvement in a curtain rod cornice adapted for use on windows to provide a cornice whereby the curtain shade and drape rods 5 may be mounted on the window and concealed from view.

It is an object of the present invention to provide a device of this class which will be simple in structure, economical of manufacture and highly efficient in use.

Another object of the invention is the provision in a device of this kind of a cornice having swingable end sections whereby the cornice may be adjusted to accommodate 15 windows of various widths.

Another object of the invention is the provision of adjusting means for adjusting the cornice to accommodate various widths and for locking the cornice in position for use 20 on windows of various widths.

Another object of the invention is the provision of rod engaging and supporting members adapted for use at various positions of adjustment of the cornice.

Other objects will appear hereinafter.

The invention consists in the combination and arrangement of parts hereinafter described and claimed.

The invention will be best understood by 30 a reference to the accompanying drawing which forms a part of this specification and in which,

Fig. 1 is a front elevational view of the invention showing it applied.

Fig. 2 is a top plan view of the invention.

Fig. 3 is a fragmentary sectional view of one end of the invention.

Fig. 4 is a sectional view taken on line 4—4 of Fig. 1.

Fig. 5 is a sectional view taken on line 5—5 of Fig. 3.

The invention comprises a front plate 9 hingedly mounted on the opposite ends of which are end sections 10 and 11. Mounted 45 on the front plate 9 is an adjusting retainer 13 through which extends a bolt 14 having a nut 15 threaded thereon, this bolt being projected through an elongated slot 16 formed in the plate 13 and through the arm 50 or brace 17 which pivotally connects to the

end piece 11. The same arrangement is adopted for both ends. By loosening the nut 15 the end pieces 11 and 12 may be moved to the desired angularity relatively to the front plate 9 so as to extend or reduce the width of the device depending upon the width of the window or windows with which used. Mounted on the end pieces 10 and 11 pivotally are retainers 18 provided with slots and openings for the reception of the trunnion 19 of the shade roller 20 for the shade 20'. Formed on the inner surface of the front plate 9 and the end pieces 10 and 11 are spaced grooves 21 and 22 in which the folded over ends of the drapes 23 and curtains 24 55 may be engaged and held in position by the rods or fillers 25, which are held in position by the clamping member 26. A spacing block 27 is shown mounted on the medial line of the front plate 9 and at opposite sides of the spacing block 27 are mounted the retainers 18, thus arranging the device for use with 60 double windows.

With a device constructed in this manner, the mounting of the curtain rods and drape rods may be easily and quickly effected without defacing the building or window casing and at the same time an attractive and pleasing appearance presented as the outer surface of the plate 9 and the end pieces 10 and 11 may be suitably ornamented. Furthermore, by the adjustable features, the device is adapted for universal use.

While I have illustrated and described the preferred form of my invention, I do not 75 wish to limit myself to the precise details of structure shown but desire to avail myself of such variations and modifications as come within the scope of the appended claims.

Having thus described my invention, what I claim as new and desire to secure by Letters Patent is:

1. A curtain rod cornice of the class described: a front plate having on its rear face 95 a pair of parallel longitudinally extending grooves formed therein for the reception of fabric supported thereon; a filler for engaging in each of said grooves and locking the fabric in position; and common means 100

for locking each of said fillers in locking position.

2. A cornice of the class described, comprising: a front plate; end sections, each hingedly connected to one end of said front plate; means for adjusting the angularity of said end sections to said front plate; a retainer swingably mounted on the inner surface of each of said end sections; a spacing block projecting rearwardly from the rear face of said front plate; and a retainer mounted on opposite faces of said spacing block.

In testimony whereof I have signed the foregoing specification.

JOHN AJEMIAN.
